UNITED STATES PATENT OFFICE.

BENJAMIN W. DODSON, OF GENEVA, ILLINOIS.

STOVE.

No. 851,280.

Specification of Letters Patent.

Patented April 23, 1907.

Application filed July 3, 1906. Serial No. 324,572.

To all whom it may concern:

Be it known that I, BENJAMIN W. DODSON, a citizen of the United States, residing at Geneva, in the county of Kane and State of Illinois, have invented certain new and useful Improvements in Stoves, of which the following is a specification.

This invention relates to improvements in steel cooking ranges, and is designed primarily for the purpose of reducing the cost of manufacture and producing an economic structure, for burning various grades of fuel.

The prime object of the invention is to provide a specially constructed air heating chamber entirely surrounding the fire pot. Air exit openings are provided in the chamber at appropriate points to introduce a series of individual streams of heated air across the fire pot, to combine and mix with a series of individual streams of heated air introduced through exit openings in a tapered chamber supported by the top of the stove.

A further object of the invention is to produce a stove for use in burning bituminous fuel, and which may be dismantled with little inconvenience, whereby it may be converted into a wood or hard coal burning stove.

In the construction and arrangement of the parts I have constantly had in view the necessity of arranging the details of construction to produce a steel range adapted for use in any locality to accommodate the various grades of fuel for cooking purposes.

To this end the invention also comprehends improvements in the specific details of construction and arrangement of parts, all of which will be hereinafter described and particularly pointed out in the claims.

In the drawings—Figure 1 is a vertical section of my improved stove, taken through the fire pot. Fig. 2 is a transverse section on the line 2—2 of Fig. 1. Fig. 3 is a view similar to Fig. 1, with the air introducing means used when burning bituminous fuel removed, and showing the structure adapted for burning wood. Fig. 4 is a transverse section on the line 4—4 of Fig. 3. Fig. 5 is a detail perspective view of the upper air heating chamber, parts being separated. Fig. 6 is a detail horizontal section of a portion of the fire pot lining to bring out more particularly the details of construction. Fig. 7 is a detail section on the line 7—7 of Fig. 3.

The numeral 1, indicates a stove casing comprising a top 2; front 3, and sides 4 and

5. The front 3, is provided with an outwardly extending opened feed chute 6, and hinged to the front of the top at 7, is a door 8. This construction provides a means whereby fuel may be introduced to the fire pot from the front of the stove. The upper part 9, of a front lining section 10, is seated in a notch 11, in the chute 6, and the two faces of said latter portion and top 9, are in alignment to provide an uninterrupted inclined plane to direct fuel into the fire pot. The front lining section 10, is spaced from the front 3, and terminates a short distance from the ends 4 and 5, but the upper portion 9, fits snugly the curved ends of the front 3. The space formed between the end walls and the front section 3, and the lining section 10, forms an air heating chamber 12, air being introduced thereto from the atmosphere through an opening 13, controlled by a damper 14, located under the feed chute. The lower edge of the front lining section 10, is notched at 15, to receive the edge portion 16, of a sub-grate 17, provided with a horizontal flange 18, supported at the front on a flange 19, extending from the front 3. The horizontal flange 18, and the edge portion 16, extends entirely around the fire pot, but the sides and end portions are somewhat lower than the front as clearly shown in Figs. 1 to 3.

The side 4, is provided with an extension 20, formed in its face with an opening 21, in which is hinged a door 22, for the introduction of logs, when it is desired to burn wood in place of bituminous, or hard coal. The opposite side 5, in line with the extension 20, is provided with a box like extension 23, to receive the ends of the logs, inserted through the opening 21. The end lining sections 24, are substantially alike and are spaced from the sides 4, and 5, to form a continuation of the air heating chamber 12, the ends of said sections of the linings fitting in seats 25, formed in the front lining section 10, and the rear lining section 26, by flanges 26^a. The lower ends of the end lining sections 24, are formed with notches 27, similar to the notches 15, in lining section 10, and seated in these notches is the upper edge flange 16, of the sub-grate; the horizontal flange 18, formed at the ends of said sub-grate being supported on inwardly extending horizontal flanges on the sides 4, and 5, while the other ends of said sections extend outwardly and fit snugly against the sides 4, and 5, below the

top 2. The inner faces of the end lining sections have overhanging horizontal flanges 2^a, to form a series of passages for free circulation of air around the sides of the fuel.

5 The rear lining section 26, forms an important part of my invention, and the details of construction thereof are quite essential to the practical operation of the stove. It is provided at its upper edge with an overhanging 10 flange 32, which rests on the top of an oven 33, while its lower end is notched at 34, to receive the edge 16, of the sub-grate, and on its rear, said rear section is provided with several lugs 35, to bear against the oven to 15 properly space it therefrom. The space between the rear lining and the oven forms a continuation of the air heating chamber 12, the ends of the rear lining section, terminating 20 a short distance from the sides of the stove. On the inner face of the rear lining section, and near the ends thereof are the flanges 26^a, to form the seats 25, hereinbefore described. When assembled the ends 25 of the lining sections 24, overlap the ends 38, of the front and rear lining sections 10, and 26, to form a neat and tight fire pot construction.

The rear lining section 26, is formed on its inner face with a series of horizontal overhanging flanges 39, and directly under these flanges with a series of tapering air exit openings 40, communicating with the chamber 12, and the fire pot. Below the sub-grate construction is the grate proper, indicated at 41, 35 which may be of any preferred construction, but preferably composed of two concavo-convex rocking members 42, mounted in a frame 43. When the grate is positioned as shown in Fig. 1, the surface 42^a, forms a 40 continuation of the sub-grate 17, making a basket like grate construction. But when it is desired to burn wood the convex surface 42^b, of the grate is brought to the top to reduce the size of the fire pot. The fingers 17^a, 45 of the sub-grate depend toward the grate proper, and are spaced therefrom, which serves to admit air around the lower portion 50 of the body of the fuel in the fire pot, air being admitted to the ash pit 43^a, through an opening, controlled by a damper 45.

The construction thus far described comprises an air heating chamber entirely surrounding the fire pot above the grate, to thoroughly heat the air before it is finally delivered to the fuel at the rear. From actual 55 experience I find that the air delivered through the openings 40, is fed to and above the body of fuel with such force as to direct it almost entirely across the interior of the fire 60 pot before the draft takes hold of it to draw it through the exit flue 46, which very materially assists in igniting the gases drawn toward the exit flue. The air introduced at the bottom of the fuel from the ash pit, 65 operates with the air introduced through the

openings 40, and a thorough mixing action of air and gas takes place, to assist in creating approximately perfect combustion before the exit flue is reached.

The tendency of the streams of air introduced to the fire pot through the openings 40, to rise immediately, to the exit flue, under the influence of the draft, is counteracted by air introducing means located to direct streams of air downwardly in the fire pot. 70 The means I employ to accomplish this purpose comprises a front plate 47, and rear plate 48, secured together at the ends at 49, to form a tapering air chamber 50. This chamber 50, is considerably wider at the top than 80 at the bottom, so that as the air is introduced thereto, it becomes somewhat heated and congested before being delivered through exit openings 51, in the bottom. Air introduced downwardly in the fire pot is reversed 85 by the draft, as clearly indicated by the arrows 52, and co-operates with the streams of air introduced through the openings 40, and retards the exit of the latter. On the outer 90 ends of the front section 47, of the chamber 50, are notches 53, adapted to engage with a fastening means 54, depending from the top 2, of the stove. In the top 2, is formed a seat 55, in which the upper end of the air heating chamber 50, fits, and is securely held 95 therein by the fastening device 54. A series of openings 57, in the stove top 2, register with the air heating chamber 50, for the introduction of air to the latter, said openings being controlled by a damper 58, whereby the 100 air introduced to the fire pot through the openings 51, may be entirely or partially cut off as may be found desirable.

For burning bituminous fuel the stove will be arranged as shown in Figs. 1 and 2, fuel 105 being introduced through the chute, the air heating chamber forming the rear of the latter, which arrangement causes the air jets passing through the openings 51, to be distributed, partially to the green fuel, and partially to the incandescent mass of fuel in the fire pot. I find this essential, because when the green fuel first contacts with the incandescent mass in the fire pot, the gas is quickly 110 liberated, and must be under control before 115 the draft draws it to the exit flue 46. Therefore, the air jets from the openings 51, introduced in the path of the streams of air coming from the openings 40, the latter streams 120 of air are deflected and mixed with the rising gases, the approximate course of the air being indicated by the arrows 60. This action of the two series of streams of air serves to mix the newly generated gas with the intense 125 heat of the incandescent mass, which is located at a point somewhat remote from the green fuel, when the latter is first introduced to the fire pot.

From actual use I have found the air designed to improve combustion must be sub- 130

jected to an extreme heating surface before it is used as a practical element to mix with the fuel, and with this in view, I find that by taking the air in at the front, and passing it entirely around the fire box, by the time it passes through the openings 40, it is heated to such a degree as to be of practical utility in improving the combustion, as it is necessarily heated to a point where it very readily co-operates with the combustion rising from the mass of fuel. This important effect I have also found is materially augmented by directing the air from the air heating chamber 50, across the line of the streams of air introduced from the exit openings 40; the location of the exit flue 46; and the drawing in of the air from the ash pit. These various currents of air coming into the fire pot as they do, cause an agitation and mixing of the gas and air, as will be readily understood. In dealing with the trade, I have also found that in order that a stove may be practical in all section of the country, it is essential that it be so arranged for use for bituminous fuel, hard coal, or wood. When using it for burning hard coal, the air heating chamber 50, is detached by releasing the attaching means 54, and removing it entirely from the fire pot, and substituting for the lining sections ordinary brick lining sections "not shown." Under these conditions it is not necessary to introduce air to the top of the fuel, nor is it essential that the heated air be delivered to the rear of the fire pot, since the air introduced through the ash pit is quite sufficient to give the desired results. For burning wood, the end lining sections 4, and 5, are removed, also the air heating chamber 50, and if desired the front and rear lining sections 10 and 26. However, it is not absolutely necessary that the two latter sections be taken out, it being rather preferable that they remain in to protect the front 3, and the oven, but this is a matter of discretion with the attendant. Under these conditions, substantial logs of wood may be burned in the fire pot by passing the same through the opening 21, its ends resting in the extension 23. The air from the ash pit is quite sufficient to promote combustion in the fire pot when the stove is arranged for burning wood, as described.

What I claim is—

1. In a stove, the combination with a casing, a fire pot mounted in the casing and composed of a series of lining sections spaced from the casing to provide an air heating chamber around said fire pot, one of said lining sections having an extension adjacent a feed chute formed in the casing, a feed chute in the casing, the rear lining section being formed with a series of tapered openings to afford communication between the air heating chamber and the interior of the fire pot, means for introducing air to said chamber, and an air heating chamber depending toward

the fire pot and formed with a series of openings located to deflect the air introduced through the openings in the rear lining section, said latter air heating chamber forming one wall of the feed chute. 76

2. In a stove, the combination with a fire pot, an air heating chamber surrounding the fire pot, and formed in the rear with a series of tapered air inlets, means for introducing air from the atmosphere to the air heating chamber, the streams of air introduced through the tapered openings in the rear of the fire pot being directed across said fire pot, an exit flue above the openings in the fire pot lining, an air heating chamber depending from the top of the stove and formed with openings below the exit flue to deflect the streams of air coming through the fire pot openings, and means for introducing fuel to the fire pot in front of the depending air heating chamber. 75 80 85

3. In a stove, the combination with a casing, a fire pot within the casing, means for introducing a series of streams of air across the fire pot, a depending tapered air heating chamber having exit openings at or near the bottom thereof, said depending air heating chamber being formed in sections, means for securing the sections together, previous to placing the air heating chamber in position in the casing, detachable means for securing the depending air heating chamber to the casing, a feed chute in front of the depending air heating chamber, and a door covering the chute. 90 95 100

4. In a stove, the combination with a casing, a fire pot within and spaced from the casing, said fire pot having a series of horizontal overhanging flanges and formed with openings below the flanges to introduce air from the air heating chamber across the fire pot, a depending air heating chamber formed with openings to introduce air downwardly in the path of the streams of air introduced across the fire pot, and a feed chute for introducing fuel in advance of the depending air heating chamber. 105 110

5. In a stove, the combination with a casing, a fire pot within the casing, means for introducing streams of air across the fire pot, an exit flue located at the upper end of and at the rear of the fire pot, a feed chute located in front of the fire pot, the bottom of said feed chute being below the bottom of the exit flue, and a depending air heating chamber formed with openings for introducing air downwardly in the path of the streams of air introduced across the fire pot, the openings of the depending air heating chamber being located on a line between the bottom of the feed chute and the bottom of the exit flue, said air heating chamber being formed in sections, means for securing the sections together previous to positioning said air heating chamber in place in the casing, and means 115 120 125 130

for attaching and detaching the air heating chamber.

6. In a stove, the combination with a casing formed with an opening, a fire pot within and spaced from the casing to form an air heating chamber entirely around said fire pot, a damper co-operating with the opening in the casing to regulate the air introduced in the air heating chamber, over hanging flanges on the inner side of the fire pot, said fire pot having tapered openings under the flanges to inject streams of air across the fire pot, means for introducing individual streams of air downwardly across the path of the streams of air coming from the tapered openings, means for introducing air to the bottom of the fire pot, and an exit flue located above the tapered openings.

7. In a stove, the combination with a casing, a fire pot formed with tapering openings

to inject streams of heated air across the interior of the fire pot, a feed chute, a depending air heating chamber formed with openings to introduce streams of air downwardly in the path of the streams of air coming from the tapered openings, the bottom of the air heating chamber being above the bottom edge of the chute to provide ample space to cause the streams of air which cross the fire pot to be mixed with the downward currents of air, and an exit flue located above the plane of the tapered openings. 25 30

In testimony whereof I have signed my name to this specification in the presence of two subscribing witnesses.

BENJAMIN W. DODSON.
